UNITED STATES PATENT OFFICE.

HERMAN B. STRATE, OF GRAND RAPIDS, MICHIGAN.

SUPPORT FOR BRICK ARCHES.

SPECIFICATION forming part of Letters Patent No. 701,960, dated June 10, 1902.

Application filed August 29, 1901. Serial No. 73,635. (No model.)

To all whom it may concern:

Be it known that I, HERMAN B. STRATE, a citizen of the United States, residing at Grand Rapids, in the county of Kent and State of Michigan, have invented certain new and useful Improvements in Supports for Brick Arches; and I do hereby declare the following to be a full, clear, and exact description of the invention, such as will enable others skilled in the art to which it appertains to make and use the same.

My invention relates to improvements in supports for brick arches, and more particularly to such supports for fire-brick arches in metal-working furnaces; and its object is to provide a durable and practical device having means for readily adjusting for any shrinkage of the brick by the action of the fire and to provide the device with certain new and useful features, hereinafter more fully described, and particularly pointed out in the claims, reference being had to the accompanying drawings, in which—

Figure 1 is a side elevation of a device embodying my invention; Fig. 2, a plan view of the same, and Fig. 3 a vertical section of the same on the line 3-3 of Fig. 2.

Like letters refer to like parts in all the figures.

30 A represents the bricks forming one section of the arch, the entire arch consisting of a number of sections supported by a series of devices such as herein shown.

B are two plates, preferably of cast-iron, arranged in parallel vertical planes and curved laterally to conform to the curvature of the arch. The lower edges of these plates engage the upper convex surface of the bricks A. Extending transversely between these plates B and near the middle thereof is a cross-bar D, having perforated lateral lugs D' to engage the transverse binding-bolts E, and also provided with an opening D" to attach any suitable tackle for hoisting the device as occasion may require. At each end of the plates B are bolts F, which bolts serve to connect the plates and also form pivotal attachments for the grippers G, which grippers are thus hinged to the respective ends of the plates B and extend downward and adjustably engage the respective ends of the series

of bricks A. Near each end of the plates B are transverse bars C. Bolts H extend through the bars C and also through openings in the grippers G and are provided with 55 adjustable nuts I at their outer ends. By turning these nuts the grippers G are adjusted from time to time as occasion may require to securely clamp the bricks A in place. By using the bars C and short bolts these 60 parts are close to the ends and do not become heated and expanded and the bolts are readily placed in position, and in the event that one should break another is readily inserted. The transverse bars C and D are detachably 65 inserted at each end in suitable radial grooves in the plates B. By removing the bolts E and F the side plates and connecting-bars may be separated for transportation or storage.

The device is also simple and durable and 70 any portion easily replaced when burned out, and when in use as the bricks shrink the grippers can be readily tightened by a wrench applied to the nuts I and the bolts H.

Having thus fully described my invention, 75 what I claim, and desire to secure by Letters Patent, is—

1. The combination of curved plates arranged in parallel vertical planes, a series of detachable bars and bolts for connecting the 80 plates, grippers pivoted to the plates, bolts connected to the bars at one end and passing through the grippers, and nuts on the bolts to adjust the grippers, substantially as described.

2. The combination of curved plates arranged in parallel planes, a bar connecting the middle of the plates and having perforated lugs at each side, bolts passing through the plates and lugs, bars connecting the plates near the ends thereof, bolts connecting the 85 ends of the plates, grippers pivoted on said bolts, bolts passing through the end bars and grippers, and nuts on the bolts to adjust the grippers, substantially as described.

3. In combination with a brick arch, laterally-curved plates arranged in parallel planes, and having their concave edges engaging the convex top of the arch, grooves in the adjacent sides of the plates and near the ends thereof, detachable transverse bars inserted in the 90 grooves, grippers pivoted to the plates and engaging the opposite ends of the arch, bolts

connecting the bars and grippers, and nuts on the bolts to adjust the grippers, substantially as described.

4. In combination with a brick arch, laterally curved plates arranged in parallel planes, and having grooves in their adjacent sides, said grooves being located at the ends and center of said curved plates, a transverse bar near the middle of the plates and having its ends 5 in the opposing grooves, lugs on the bar, bolts extending through the plates and lugs, transverse bars near the ends of the plates, and

having their ends in opposing grooves, transverse bolts connecting the ends of the plates, grippers pivoted on said bolts, and bolts connecting the grippers to the adjacent transverse bars, substantially as described. 15

In testimony whereof I affix my signature in presence of two witnesses.

HERMAN B. STRATE.
